CLAIM

The ornamental design for a two-strap sandal, as shown and described.

DESCRIPTION

FIG. 1 is a front left-side perspective view of a two-strap sandal showing my new design;

FIG. 2 is a front right-side perspective view thereof;

FIG. 3 is a rear left-side perspective view thereof;

FIG. 4 is a rear right-side perspective view thereof;

FIG. 5 is a font perspective view thereof;

FIG. 6 is a rear perspective view thereof;

FIG. 7 is a left-side perspective view thereof;

FIG. 8 is a right-side perspective view thereof;

FIG. 9 is a top perspective view thereof; and,

FIG. 10 is a bottom perspective view thereof.

FIGS. 1-10 depict a first embodiment of a design for a left two-strap sandal; a second embodiment is a right two-strap sandal, which is a mirror image thereof.

The broken lines depict zig-zag and large scale stitching, as well as the curving single broken lines found on the footbed that form no part of the claimed design. The linear stitching found in single or double rows of broken lines upon the upper strap structure form no part of the claimed design. The broken lines on the sole of the shoe form no part of the claimed design.
